SOAP CAKE

Carl O. Swanson, Minneapolis, Minn.

Application June 16, 1941, Serial No. 398,270

3 Claims. (Cl. 252—134)

My invention relates to improvements in the cakes or bars into which ordinary toilet and cleansing soaps of all kinds are made and embodies improvements over my prior application for patent for Soap cake filed on October 18, 1940, Serial No. 361,653.

In the use of the ordinary soap cake it soon becomes worn down to a thin and relatively fragile sliver or piece which is generally unsatisfactory to use and which soon becomes 10 broken and usually is discarded. This represents a waste of this valuable material and is withal an unsatisfactory thing. It is the primary object of my invention therefore to provide means whereby the worn soap piece or sliver may be applied and attached to a new soap cake in such manner as to become a component part thereof, thus permitting the worn piece to be completely used up and thus effecting a considerable and worthwhile saving to the user.

A further object is to provide means on each new soap cake to receive the worn piece or remainder of a previously used cake and to anchor the piece firmly in place so that it adds its bit to the effective soaping surface of the composite cake.

Still another object is to provide means of this nature by which the worn piece may be readily seated upon the side of the new soap cake by hand pressure alone, and without the use of any tools, and in which provision is made to anchor the piece against slippage in any direction until it is finally completely consumed.

These and other more detailed and specific objects will be disclosed in the course of the following specification, reference being had to the accompanying drawing, in which—

Fig. 1 is a plan view of a new soap cake having means in one side to receive and anchor a worn soap piece, an end fragment of the latter being shown in place.

Fig. 2 is a cross section along the line 2—2 in Fig. 1 and showing the worn soap piece in position for application to the new soap cake.

Fig. 3 is a similar view but showing the soap piece applied to the cake.

Fig. 4 is an enlarged fragmentary section along the line 4—4 in Fig. 3.

Fig. 5 is an enlarged plan view of the single fastening point or tooth of Fig. 4.

Referring now more particularly and by reference characters to the drawing, the numeral 10 designates the new or unused soap cake or bar to which I intend to apply the worn piece or sliver 11 remaining from a used cake of the same or 55

similar kind. The cake 10 may be of any desired or usual shape and as here shown is of the flat form having opposed, usually flat, sides 12.

In accordance with my invention at least one of these sides 12 is provided with a hollowed or concaved cavity 13 which is of such shape, in plan, that it will nicely receive one rounded side 14 of the used soap piece 11. For this purpose the cavity 13 may be of elongated, oval shape, although this of course will vary somewhat in accordance with the shape of the soap cake itself, which in turn will determine the shape and size of the worn piece remaining after use.

In this cavity 13 I provide a series of spaced upstanding projections, points or teeth preferably, although not necessarily, comprising several larger center teeth 15 and smaller outer teeth 16 spaced outwardly toward the margins of the cavity. These teeth are molded on the soap cake 10 as it is initially manufactured and, to prevent possible breakage in packing and handling, the teeth are molded to such length as to fall slightly short of the plane of the side 12 in which the cavity 13 occurs.

Before being subjected to the softening effects of water and heat the soap cake 10 is, of course, rather hard and firm and as a result the teeth 15—16 may readily enter the side of the used soap piece 11 as the same is pressed into the cavity 13, as seen in Fig. 3. This action is further facilitated by the fact that the worn soap piece 11, having been in use, is usually soft and may be readily penetrated by the teeth. Obviously then, when thus mounted, the soap piece 11 is firmly held in place upon the side of the new soap cake 10 and becomes a nicely integrated part thereof, being so positioned that it may be wholly consumed by usual manipulation of the composite soap cake. However, before the new cake 10 becomes worn near to the point at which it must in turn be placed on another cake, the used piece 11, and all adjacent parts including teeth 15—16, are worn away entirely so that the used piece remaining from the cake 10 is of proper shape to fit the cavity 13 in the next new cake.

As the teeth 15—16 enter the used soap piece 11 they of course displace some of the material making up that piece and to accommodate such material I provide around the base of each of the teeth a circumferential groove 17 in the surface of the cavity 13 and of course entering or cutting below that surface. The teeth all have a generally tapering shape from base to point and as they enter the soap piece 11 the

relatively soft material may fill into the grooves 17 as clearly shown at 18 in Figs. 3 and 4. Such action not only facilitates the proper seating of the soap piece in the cavity 13 but reduces the possibility of breaking or crumbling the piece and the material forced into the grooves further aids in preventing the soap piece from slipping laterally or in an edgewise direction.

To further anchor the soap piece in place I provide the center teeth 15, and the other teeth 16 if desired, with lengthwise extended and radially projecting ribs or fins 19 which run from the sharp ends down toward the base and terminate in sharply cut off ends or end portions 20 substantially in the plane of the surface of the cavity 13. These ribs 19 enter the soap piece 11 without difficulty and as the material enters the grooves 17 as described it is guided and directed beneath the overhanging shoulder means or ledges formed at the sharply cut lower ends 20 of the ribs to thus lock against upward or outward displacement of the soap piece from the teeth.

It is understood that suitable modifications may be made in the structure as disclosed, provided such modifications come within the spirit and scope of the appended claims.

Having now therefore fully illustrated and described my invention, what I claim to be new and desire to protect by Letters Patent is:

1. The combination with a soap cake, of means for securing a used soap piece to one side thereof, said means comprising a plurality of widely separated pointed members extending from the side of the soap cake to enter the soap piece, 35

5 fins extending laterally from at least one of said members and having lower ends terminating in spaced relation to said side of the soap cake and spaced from the bases of the members to provide shoulders beneath which material displaced from the soap piece may enter to lock the soap piece against movement off the tooth.

2. A soap cake having means for fastening to one side thereof a worn soap piece, said means comprising a plurality of widely separated pointed teeth extending from the side of the soap cake to enter said piece, the said cake having a recess at the base portion of each tooth extending below the face of said soap cake side, and ribs extending from the point of at least one tooth toward said recess and terminating short of the base portion of the tooth in end portions extending outward from the tooth substantially at right angles thereto whereby material displaced from the soap piece into said recess by entrance of the tooth may lodge beneath said ends of the ribs to restrain the piece against removal from the cake.

3. A soap cake having means for fastening to one side thereof a worn soap piece, said means comprising a plurality of widely separated pointed teeth extending from the side of the soap cake to enter said piece, the said cake having a recess at the base portion of each tooth, and shoulder means extending outwardly from at least one tooth adjacent its base portion in position to be engaged by material displaced from the soap piece by the tooth and forced into said recess.

CARL O. SWANSON.
